UNITED STATES PATENT OFFICE.

WILLIAM E. LOVER, OF FINDLAY, OHIO.

NOVELTY ENVELOPE.

Application filed July 2, 1918, Serial No. 243,036. Renewed December 11, 1920. Serial No. 430,043.

To all whom it may concern:

Be it known that I, WILLIAM E. LOVER, a citizen of the United States, residing at Findlay, in the county of Hancock and State 5 of Ohio, have invented certain new and useful Improvements in Novelty Envelopes, of which the following is a specification.

This invention relates to mailing envelopes and has as its object to provide a novelty mailing envelope which will prove highly valuable as an advertising medium and which will be of considerable use to the recipient.

A further object of the invention is to 15 provide a novelty envelope designed for use in the transmittal of advertising matter or ordinary correspondence and possessing features which will influence the person addressed to retain the envelope, so that any 20 advertising matter upon the envelope will be more or less constantly brought to the attention of the person.

Another object of the invention is to provide the front and back of a mailing envelope with a rubbing surface which, in one embodiment of the invention, is to be employed in pointing pencils, and in another embodiment of the invention is to be employed as an eye glass lens cleaner. Thus 25 the envelope is of use after it has served its purpose of transmitting mail matter, and as stated above, the person receiving the envelope will be influenced, by reason of its usefulness, to retain the same together with the advertising matter thereon instead of throwing the envelope away as is usually done.

In the accompanying drawings:

Figure 1 is a perspective view of one form 40 of the envelope embodying the present invention, the closure flap of the envelope being shown open;

Figure 2 is a horizontal sectional view through the envelope;

Figure 3 is a vertical transverse sectional view on the line 3—3 of Figure 2;

Figure 4 is a view similar to Figure 3 illustrating a slight modification of the invention.

In the drawings, the envelope is indicated 50 in general by the numeral 1 and the same comprises the usual front 2 and back 3. The envelope in itself may be of any desired size and construction and may be adapted to be sealed by the usual closure flap 4, or this flap 55 may be left unsealed where advertising mat-

ter alone is to be transmitted. In that form of the invention shown in Figures 1, 2 and 3 of the drawings, a sheet of sand paper or emery cloth, indicated by the numeral 5, is secured by adhesive or otherwise to the inner face of the front of the envelope at one end thereof, and a similar sheet 6 is secured to the inner face of the back of the envelope and opposes the sheet 5. In the illustrated embodiment of the invention, 60 these rubbing sheets are located in one corner of the interior of the envelope, but it will be understood, of course, that the sheets may be larger, or in other words may be made so as to extend over a greater portion 65 of the area of the front and back of the envelope respectively, or on the other hand they may be made smaller than illustrated in the drawings and they may, of course, be positioned differently from the illustration 70 if found desirable. This form of the invention is intended to serve as a pencil pointer after the advertising matter has been removed from the envelope and the 75 said envelope has served its purpose of transmitting the advertising matter or letter. By opening the flap 4 as shown in Figure 1 of the drawings and slightly opening the mouth of the envelope, a pencil may be inserted endwise into the envelope between the sheets 5 and 6 and then moved 80 backwardly and forwardly or rotated while pressure is exerted against the outer faces of the front and back of the envelope to cause the sheets to more or less firmly bear 85 against the pencil as it is so moved. Of course, any lead and wood dust resulting from the pointing of the pencil will settle 90 in the bottom of the envelope and may be allowed to accumulate or it may be immediately dumped therefrom. In any event the lead and wood dust will be collected in 95 the envelope and not permitted to fly about and soil desk surfaces, papers or the like as occurs when an ordinary sheet of sand paper 100 is employed for this purpose.

In that form of the invention shown in Figure 4 of the drawings, the numerals 7 and 8 indicate, respectively, pieces of 105 chamois cloth which are secured by adhesive or otherwise to the inner faces of the front and back of the envelope, these pieces corresponding to the pieces or sheets 5 and 6 heretofore described. This latter form of the invention is intended to be employed as 110

a device for polishing and cleaning eye glass lenses and its usefulness will be evident in view of the foregoing description.

While the envelopes may be employed by various classes of business houses, the fact will be appreciated that the pencil pointer envelope possesses considerable value as an advertising medium for pencil manufacturers, dealers in stationery, etc., and that the lens polisher envelope possesses value as an advertising medium for use by opticians, jewelers, etc.

It will be understood that the front of the envelope may be provided with the usual or any preferred type of window or opening through which the name and address upon the letter head may be viewed.

It will be understood from the foregoing that the envelope constitutes a receptacle having flexible walls normally lying close to each other and provided interiorly with the abrading surfaces mentioned so that parti-

cles removed by the abrading surfaces will be collected and retained within the receptacle.

Having thus described the invention, what is claimed as new is:

1. The combination with a relatively flat flexible walled receptacle, closed except for an open mouth, of a sheet of emery cloth or paper secured upon the inner faces of the front and back of the receptacle, the sheets opposing each other.

2. A receptacle closed except for an open mouth and having flexible walls normally lying close to each other and provided interiorly upon the opposing faces of its said walls with opposed abrading surfaces, the receptacle being designed to receive and collect material removed by abrasion from an object moved between and in contact with said surfaces.

In testimony whereof I affix my signature.

WILLIAM E. LOVER.
